[57] CLAIM

The ornamental design for the table base, as shown and described.

DESCRIPTION

FIG. 1 is a perspective view of the table base comprising my new design;

FIG. 2 is a top plan view thereof;

FIG. 3 is a front elevation view thereof;

FIG. 4 is a rear elevation view thereof;

FIG. 5 is a bottom plan view thereof;

FIG. 6 is a perspective view thereof in use with a round table top; and,

FIG. 7 is a perspective view thereof in use with a square table top.

“The broken lines are for environmental purposes only and form no part of the claimed design”.
